Primary Examiner — Susan Bennett Hattan*Assistant Examiner* — Landon Thomas Cassell(74) *Attorney, Agent, or Firm* — Rumit Ranjit Kanakia(57) **CLAIM**

The ornamental design for a RF eye massager, as shown and described.

DESCRIPTION

FIG. 1 is a first perspective view of a RF eye massager showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines, shown in the drawings depict portions of the RF eye massager in which the design is embodied that form no part of the claimed design.
